UNITED STATES PATENT OFFICE.

ADOLF MARTIN KOBOLKE, OF GILDEROY, VICTORIA, AUSTRALIA.

APPARATUS FOR DRYING AND SEASONING TIMBER.

Application filed July 25, 1923, Serial No. 653,613, and in Australia July 25, 1923.

This invention relates to a process and apparatus for seasoning timber in log, board and other shape and has been devised in order to provide a process of greater utility than those at present in use.

With the processes of seasoning or drying timber at present in use the timber is dried from outside application to the inside with the result that in processes other than slow methods of seasoning it must be subjected to the action of steam or fluids to re-open the cells to allow the timber to be dried, and this is caused through the circulation of fluids past the boards.

This invention has been devised in order to overcome existing defects and to provide an improved process of great utility.

An essential feature underlying this invention consists in subjecting the timber to vacuum to perform the function of drying the timber, such function being characterized in that the vacuum draws the moisture and sap from the inside to the outside and embodies the basic principle underlying the invention.

In this function the cells of the timber are adjusted to atmospheric pressure and when the vacuum is created the pressure is released and the cells exude towards the vacuum and no circulation of current takes place but the moisture and sap exude and are then evaporated or condensed and drawn off by the vacuum.

A further essential feature consists in subjecting the timber to heat and interchanging the degree of vacuum employed according to the heat to which the timber is subjected, that is to say, the lower the heat the greater the vacuum and the higher the heat the poorer the vacuum.

A further essential feature embodied in the invention consists in applying the vacuum to the timber as shown as the heat reaches the required temperature so that the vacuum draws the sap from the centre to the surface of the timber, such function being the most effective continuous manner of drying timber and obviates any further treatment.

This moisture absorbing agent may be a lime or other chemical to effect the purpose.

Steps in the process therefore consist in subjecting the timber to excessive heat to release the moisture therefrom, exhausting the moist atmosphere by an exhauster, such as a vacuum pump or pumps and condensing

or absorbing the unexhausted moisture released from the timber so as to increase the drying of the timber in the kiln.

In carrying the invention into practical effect a chamber or kiln capable of being hermetically sealed is provided and is constructed of concrete, metal or other suitable material.

The timber to be treated is stacked or run into this chamber which is also fitted with the connections to one or more vacuum producing machines the vacuum pump of the machine being disposed externally or internally of the chamber and being fitted with an exhaust.

Any suitable vacuum producing machine may be employed to exhaust the moisture and sap from the wood being treated.

Additionally the timber may be subjected to heat radiation by steam pipes or other elements in which case when the sap or moisture is sufficiently heated the vacuum is applied and the sap is drawn from the centre of the timber evenly to the outer surface, although it will be readily understood that the heat and vacuum may be simultaneously applied if so desired.

It is preferred that the heat and vacuum may be interchanged by controlling both elements in such a manner that the higher the heat subjected to the timber the poorer the vacuum and the lower the heat the greater the vacuum.

Additionally to the apparatus above described one or more condensers consisting of a system of piping or a narrow chamber of maximum area with a circulation of air or cold water is placed above the kiln, and it is obvious that any other suitable construction of condenser may be employed if so desired for instance a chemical absorber of moisture may be used.

When one condenser is employed it is preferably disposed centrally above the kiln and the moisture not exhausted by the vacuum machine or machines condenses on the surface or lining of the kiln and runs off through an outlet pipe which externally of the kiln is provided with shut off cocks with a trap between so that the atmosphere cannot reach the kiln interior.

Thus two temperatures are maintained about the kiln, viz the heat inside and the condensers outside which with the vacuum machines give the correct balance or ratio for drawing off the whole release of mois-

ture from the timber which is thus seasoned continuously in a much shorter time and in a simpler manner than is obtained in the methods at present in use.

5 In order that the invention may be more readily understood it will now be described with reference to the accompanying drawings in which:—

10 Figure 1 is a view in elevation showing the kiln and vacuum producer in cross section of a plant constructed according to this invention.

Figure 2 is a view in cross section of a modified construction of kiln.

15 Figure 3 is a view in cross section of a kiln electrically heated embodied in the invention.

20 Figure 4 is a view in cross section of a kiln embodied in the invention formed of concrete, and

Figure 5 is a view in section of the means for holding the door to the kiln.

According to this invention a steam boiler 1 is provided or an electric heater or furnace 2 as illustrated in Figure 3 may be employed.

25 In the arrangement illustrated in Figure 1 a water boiler 1 is provided having a pipe lead 3 for the steam with valve control 4 to the steam coils or tubes 5 in a kiln 6.

30 This kiln 6 may be of any suitable material and construction being fitted with a glass dome 7 within which is a thermometer 8 the dome 7 indicating the extent of condensation in the kiln and also being a gauge when suddenly cooled down to show any indication of moisture in the kiln.

35 In the kiln 6 on suitable supports or trays 9 are disposed the boards 10 placed preferably at an angle as illustrated.

40 In order to prevent the condensation products running over the boards 10 deflecting plates 11 are fitted on the kiln and the moisture is run off through the pipe 12 past the valve 13 to the trap 14 which at its delivery pipe is provided with a valve 14^a to prevent the return of air to the kiln.

45 Leading from the pipe 12 is a further pipe 15 fitted with a valve 16 leading to a vacuum producing device 17 of any suitable construction, said device 17 being fed by water or other fluid fed through the pipe 18 under pressure.

50 Any suitable number of vacuum producing devices 17 may be employed and when the sap and moisture in the boards 10 reach a sufficient temperature imparted by the heat of the coils 5 the vacuum devices 17 are caused to operate so drawing the moisture from the wood in the manner above described, but if desired the vacuum devices may commence to operate simultaneously with the heat or at any degree thereof.

55 In order to quickly condense the moist

vapours drawn or given off from the wood a condenser or condensers is or are employed. This condenser preferably consists of a pipe 19 adapted to spray water or air through the spray pipe 20 above the kiln 6 and on the outer surface thereof. The operation is continued until the required dryness is apparent in the glass dome 8 as such then indicates that the required moisture and sap has been drawn from the wood and that the wood is seasoned or dried.

60 In the construction of kiln illustrated in Figure 2 the vacuum device or devices 17 is or are disposed in the kiln 6 and exhausts the moisture and gas through the exhaust pipe 21.

65 A further modification in this figure shows the boards 10 mounted on trays 22 on a carriage 23 supported on wheels 24 running on rails 25 thus allowing of the rapid handling of the boards to and from the kiln 6.

70 In the modification illustrated in Figure 3 the kiln is electrically heated, a heater being provided in the kiln 6 by the insertion of electrical heating devices 26 of any suitable construction but preferably encased in insulation so that a short circuit is prevented in the heating chamber or kiln 6.

75 In this kiln 6 are trays 9 carrying the boards 10 to be treated on a carriage working on rails if desired, while the moisture deflectors 11 may also be fitted the moisture and gas being drawn through the pipe 12 by the vacuum device or devices 17 as above described.

80 The kiln door 30 is preferably hermetically sealed by the vacuum in the kiln 6, the door 30 being held against a rubber packing ring 31 extending from the groove 32 in the end of the kiln frame as illustrated in Figure 5, the door being loosely hinged at the top as at 33 or the side to allow of movement on the operation of the vacuum in the kiln and so cause the hermetic sealing of the door while the vacuum is in operation.

85 In the modification illustrated in Figure 4 the kiln 6 may be formed of concrete in which case it is preferred that a water jacket 34 be formed on both sides as illustrated to assist the condensation of the moisture in the kiln as above specified, the wall forming the condenser, and it is thus obvious that the kiln may be almost completely immersed in water when condensing or alternatively in some instances the condensing agents need not be employed as the moisture would be withdrawn in the form of vapour.

90 It is obvious that any suitable form of vacuum producing device may be employed the construction illustrated being suitable for the purpose and comprises the device 17 having the fluid inlet pipe 18 for delivering the fluid under pressure past the whirling screw 17^a in the nozzle 17^b where the fluid as it leaves the nozzle is caused to spread

against the walls of the exhaust passage 17^c so as to form a wall of fluid with a hollow centre 17^d into which the matter being exhausted is drawn by centrifugal force 5 through the pipe 15 from the kiln 6.

I desire it to be understood that various improvements and modifications may be embodied without departing from the spirit and scope of the invention the essential feature of which is subjecting timber to vacuum so that the sap is evenly drawn from 10 the centre to the outer surface.

What I claim as my invention and desire to secure by Letters Patent is:-

15 1. Apparatus for drying and seasoning timber, comprising a hermetically sealed kiln for receiving timber to be treated, a boiler, piping in the kiln for receiving steam from the boiler, a trap, a pipe leading 20 from the kiln to the trap, a vacuum pump, a branch from the pipe to the pump, and a condenser operative to cause condensation inside of the kiln, for the purposes specified.

2. Apparatus for drying and seasoning

timber, comprising a hermetically sealed 25 kiln for receiving timber to be treated, means for supplying heat to the interior of the kiln, a trap, a pipe leading from the kiln to the trap, a vacuum pump, a branch from the pipe to the vacuum pump, and 30 means for causing condensation inside of the kiln, for the purposes specified.

3. Apparatus for drying and seasoning timber, comprising a hermetically sealed 35 kiln for receiving timber to be treated, means for supplying heat to the interior of the kiln, a vacuum pump arranged to exhaust moisture given off from the timber in the kiln, a condenser for the kiln for assisting condensation within the kiln of the 40 moisture therein, and means for feeding the timber to the kiln including trays mounted on a carriage and running on rails, substantially as described.

Signed at Melbourne, Victoria, Australia, 45 this 26th day of April, 1923.

ADOLF MARTIN KOBIOLKE.
